DISTRIBUTOR STRUCTURE

Harold P. Faris, Philadelphia, Pa., and John E. White, Trenton, N. J., assignors to National Automotive Fibres, Inc., Detroit, Mich., a corporation of Delaware

Application April 24, 1943, Serial No. 484,431, which is a division of application Serial No. 363,196, October 28, 1940. Divided and this application September 27, 1943, Serial No. 504,012

12 Claims. (Cl. 91—8)

This invention relates generally to carpet making machines for manufacturing carpet of the cemented pile type and constitutes a division of our application filed April 24, 1943, bearing Serial No. 484,431, which is a division of our application filed October 28, 1940, bearing Serial No. 363,196.

One of the essential objects of the invention is to provide an improved distributor for feeding cut fibers, such as cut hair and the like, onto a cement coated surface of suitable carpet material, such as a burlap covered base of rubber, while the carpet material is being vibrated so that the vibration will cause the fibers discharged from the distributor to be imbedded endwise in the cement to simulate the pile of a conventional woven carpet.

Another object is to provide a distributor provided with means for breaking up balls, pills, or other objectionable formations of the fibers.

Another object is to provide a distributor wherein the means for breaking up the balls, pills, etc., of fibers is in the form of cooperating saw-toothed blades carried by spaced horizontal shafts that rotate in opposite directions.

Another object is to provide a distributor wherein the saw-toothed blades may be adjusted relative to each other to vary the clearance therebetween.

Another object is to provide a distributor wherein the blades mentioned are adapted to tear the balls, pills, etc., apart so that the fibers will be in substantially free and loose condition as they pass downwardly from the lower end of the casing onto the cement coated surface of the carpet material.

Another object is to provide a distributor that is simple in construction, economical to manufacture, easy to install and efficient in operation.

Other objects, advantages and novel details of construction of this invention will be made more apparent as this description proceeds, especially when considered in connection with the accompanying drawings, wherein:

Figure 1 is a side elevation of a machine for making carpet and having a distributor embodying our invention;

Figure 2 is an elevational view of the distributor;

Figure 3 is an end view of the distributor illustrated in Figure 2;

Figure 4 is an enlarged vertical sectional view through the lower portion of the distributor illustrated in Figures 1 and 2;

Figure 5 is a sectional view taken substantially on the line 5—5 of Figure 4.

Referring now to the drawings, A is a distributor embodying our invention and constituting a part of a machine illustrated generally in Figure 1 for manufacturing carpet of the cemented pile type.

As shown in Figure 1, the carpet material 10, such as burlap covered rubber, is advanced 10 through the machine with the burlap side thereof of uppermost so that the upper surface of the burlap may be coated or covered with an adhesive substance or cement as the material passes through an adhesive applying mechanism 11. Cooperating belts 12 and 13 respectively are employed for withdrawing the carpet material 10 from a roll 14, and other conveyor means including a belt 15 is employed for advancing the carpet material through the adhesive applying mechanism 11 and over suitable rotary beaters 16 which vibrate the material after the adhesive substance is applied to the upper surface thereof.

Cut fibers such as cut hair or the like are discharged from the distributor A, and from a rotary sieve (not shown) located between the adhesive applying mechanism 11 and the distributor A onto the adhesive coated carpet material as it is vibrated so that such fibers will be imbedded in the adhesive coating to form the cemented pile carpet. If desired the fibers supplied to the distributor A constituting the second point of application may be excess fibers from the sieve mentioned constituting the first point of application. Moreover, such excess fibers may be mixed with a certain percentage of freshly cut fibers for the second application.

Preferably the distributor A has a casing 20 that is relatively narrow and elongated in configuration so as to extend transversely over the advancing carpet material 10 on the belt 15, hingedly mounted deflector plates (not shown) for directing a portion of the cut fibers toward opposite ends of the casing 20, and rotary saw-toothed blades 22 for breaking up balls, pills or other formations of the cut fibers.

The casing 20 is provided at its upper end with an inlet 30 through which the cut fibers are adapted to pass from a collector or other suitable source of supply (not shown), and has an open lower end 31 through which the cut fibers are adapted to be discharged onto the adhesively coated carpet material 10. 32 are windows in one side of the casing 20 through which the operator can inspect the mechanism within the casing, and 33 are removable panels which may be

in the same or another side of the casing to afford access to the interior thereof.

Preferably the upper portion 34 of the casing is inverted V-shape in configuration, and the inlet 30 is at the apex of the V, while the lower portion 35 of said casing is substantially rectangular shape in configuration.

The saw-toothed blades 22 are in the lower portion 35 of the casing and are supported in surface to surface relation upon plates 60 fixed to flat portions 61 of horizontal shafts 62 journaled in suitable bearings (not shown) carried by the casing 20. Preferably there are five shafts 62 arranged in staggered vertically spaced relation in the casing 20 and four saw-toothed blades on each shaft. The blades 22 have transversely extending elongated slots 63 that receive suitable clamping bolts 64 carried by the supporting plates 60 so that the blades 22 may be adjusted on said plates to vary the clearance between the blades on adjacent shafts 62.

Preferably adjacent shafts 62 are rotated in opposite directions at relatively high speed by mechanism (not shown) so that the saw-toothed blades 22 carried thereby will break up the fibers, especially balls, pills, etc., thereof coming in contact therewith and will distribute the broken up or loose fibers downwardly so that they will be discharged from the lower open end of the casing 20 onto the adhesive coated carpet material 10.

In use, the fibers may be supplied to the inlet 30 of the casing 20 by any suitable means (not shown). Upon reaching the lower portion 35 of the casing the fibers aforesaid will engage the rotating saw-toothed blades 22 which will distribute the same downwardly through the lower open end of the casing onto the advancing adhesive coated carpet material 10. If some of the fibers have gathered into balls, pills or other objectionable formations, the saw-toothed blades 22 will effectively break up such balls, pills, etc., so that the separated fibers in substantially free or loose condition will be distributed downwardly through the open end of the casing onto the cement coated carpet material. Thus, all of the fibers discharged from the lower end 35 of the casing will be free and loose and will be distributed with substantial uniformity onto the carpet material.

What we claim as our invention is:

1. A distributor having a casing provided at the top thereof with an inlet and provided at the bottom thereof with an outlet, and means within said casing for breaking up balls, pills and other formations of cut fibers admitted to the inlet so that the fibers as individual elements will be discharged through said outlet, including a pair of rotatable cooperating saw toothed blades, and means for adjusting said blades relative to each other to vary the clearance therebetween.

2. A distributor having a casing provided at the top thereof with an inlet and provided at the bottom thereof with an outlet, and means within said casing for breaking up balls, pills and other formations of cut fibers admitted to the inlet so that the fibers as individual elements will be discharged through said outlet, including vertically spaced staggeredly arranged relatively adjustable oppositely rotating members operable to tear the balls, pills, etc. apart so that the fibers thereof will be in free and loose condition.

3. A distributor having a casing provided at the top thereof with an inlet and provided at the bottom thereof with an outlet, and means

within said casing for breaking up balls, pills and other formations of cut fibers admitted to the inlet so that the fibers as individual elements will be discharged through said outlet, including staggeredly arranged rotatable shafts, saw toothed blades carried by said shafts, and means for rotating said shafts in opposite directions.

4. A distributor having a casing provided at the top thereof with an inlet and provided at the bottom thereof with an outlet, and means within said casing for breaking up balls, pills and other formations of cut fibers admitted to the inlet so that the fibers as individual elements will be discharged through said outlet, including staggeredly arranged rotatable shafts, saw toothed blades adjustable on said shafts, and means for rotating said shafts.

5. A distributor of the class described having a casing provided at the top and bottom thereof with an inlet and an outlet for fibers to be distributed onto an adhesive coated carpet material, and staggeredly arranged relatively adjustable rotary saw-toothed blades within the casing for breaking up balls, pills and other formations of fibers received by the inlet and operable to distribute the fibers from said balls, pills, etc., in loose and free condition through the outlet onto the adhesive coated carpet material.

6. A distributor of the class described having a casing provided at the top and bottom thereof with an inlet and an outlet for fibers to be distributed onto an adhesive coated carpet material, and cooperating adjustable oppositely rotating saw-toothed blades within the casing operable to break up balls, pills and other formations of fibers received by the inlet and operable to distribute the fibers from said balls, pills, etc., through the outlet onto the adhesive coated carpet material.

7. A distributor having a casing provided at the top thereof with an inlet and provided at the bottom thereof with an outlet, and means within said casing for breaking up balls, pills and other formations of cut fibers admitted to the inlet so that the fibers as individual elements will be discharged through said outlet, including vertically spaced staggeredly arranged substantially horizontal shafts within said casing between said inlet and said outlet, adjacent shafts being rotatable in opposite directions, plates fixed to said shafts, and saw-toothed blades disposed in surface to surface relation upon said plates, said blades having transversely extending elongated slots, and clamping elements for said blades carried by said plates and engaging the slots in said blades whereby said blades may be adjusted on said plates to vary the clearance between said blades on adjacent shafts.

8. A distributor having a casing provided at the top thereof with an inlet and provided at the bottom thereof with an outlet, and means within said casing for breaking up balls, pills and other formations of cut fibers admitted to the inlet so that the fibers as individual elements will be discharged through said outlet, including vertically spaced staggeredly arranged substantially horizontal shafts within said casing between said inlet and said outlet, plates carried by said shafts, and saw-toothed blades adjustably mounted on said plates.

9. A distributor having a casing provided at the top thereof with an inlet and provided at the bottom thereof with an outlet, and means within said casing for breaking up balls, pills and other formations of cut fibers admitted to the inlet so that the fibers as individual elements will be dis-

charged through said outlet, including spaced oppositely rotating horizontal shafts within said casing, and cooperating saw-toothed blades carried by said shafts, said blades being adjustable on said shafts to vary the clearance between the 5 blades on adjacent shafts.

10. A distributor having a casing provided at the top thereof with an inlet and provided at the bottom thereof with an outlet, and means within said casing for breaking up balls, pills and other formations of cut fibers admitted to the inlet so that the fibers as individual elements will be discharged through said outlet, including a pair of rotatable shafts, means for rotating said shafts in opposite directions, plates on said 10 shafts at diametrically opposite sides thereof, and saw-toothed blades mounted on said plates.

11. A distributor having a casing provided with an inlet and an outlet for fibers, vertically staggered oppositely rotatable shafts within said casing between the inlet and outlet, and relatively 15 20

adjustable cooperating saw-toothed blades on said shafts for breaking up balls, pills and other formations of fibers admitted to said casing through said inlet, so that such fibers as individual elements will be discharged through said outlet.

12. A distributor of the class described having a casing provided at the top and bottom respectively thereof with an inlet and an outlet for fibers to be distributed onto an adhesive coated carpet material, and means within the casing for breaking up balls, pills and other formations of fibers received by the inlet and operable to distribute the fibers from said balls, pills, etc., in loose and free condition through the outlet onto the adhesive coated carpet material, including spaced oppositely rotating shafts, plates rigidly mounted on said shafts, and saw-toothed blades adjustably mounted on said plates.
